(57) **CLAIM**

The ornamental design for a dome-type simulator as shown and described.

DESCRIPTION

FIG. 1 is a perspective view of the dome-type simulator, showing our new design;

FIG. 2 is a front view of the dome-type simulator;

FIG. 3 is a rear view of the dome-type simulator;

FIG. 4 is a left side view of the dome-type simulator;

FIG. 5 is a right side view of the dome-type simulator;

FIG. 6 is a top view of the dome-type simulator;

FIG. 7 is a bottom view of the dome-type simulator;

FIG. 8 is a perspective view of the dome-type simulator showing exemplary environmental structure of a cockpit; and,

FIG. 9 is a top view of the dome-type simulator showing exemplary environmental structure of a cockpit.

The broken lines shown in the drawings depict portions of the dome-type simulator and exemplary environmental structure of a cockpit in FIG. 8 and in FIG. 9. All broken lines in the drawings form no part of the claimed design.
